UNITED STATES PATENT OFFICE.

PRESTON BELVIN, OF RICHMOND, VIRGINIA.

FLOOR-OILER.

1,350,638.

Specification of Letters Patent. Patented Aug. 24, 1920.

Application filed September 5, 1919. Serial No. 321,824.

To all whom it may concern:

Be it known that I, PRESTON BELVIN, citizen of the United States, residing at Richmond, in the county of Henrico and State 5 of Virginia, have invented certain new and useful Improvements in Floor-Oilers, of which the following is a specification.

This invention relates to an improved floor oiler and has as one of its principal 10 objects to provide a device whereby a coat of oil may be evenly distributed over a floor.

The invention has as a further object to provide a device employing a rubbing shoe and wherein oil will be evenly distributed 15 to the shoe for insuring an even distribution of oil by the shoe over the floor.

A further object of the invention in this connection is to provide an oil distributer in 20 connection with the shoe and wherein the distributer will be so formed that oil must overflow from the distributer in order to issue therefrom onto the shoe, this construction providing an arrangement whereby spilling of the oil in the distributer will be 25 obviated.

A further object of the invention is to provide a device wherein flow of oil from the reservoir employed to the distributer may be readily controlled as desired.

30 And the invention has as a still further object to provide a device wherein the shoe will be reinforced in such manner as to prevent buckling or distortion of the shoe so that the efficiency of the device will thus be 35 materially prolonged and wherein the reinforcing means employed in connection with the shoe may be adjustably positioned with respect thereto for either increasing or decreasing the flexible margin of the shoe 40 exposed for contact with a floor, this construction also providing an arrangement whereby said reinforcing means may be adjustably retracted as the shoe wears away.

Other and incidental objects will appear 45 hereinafter. In the drawings:

Figure 1 is a perspective view of my improved oiler,

Fig. 2 is a vertical sectional view taken 50 centrally through the device, this view more particularly showing the structural details of the oiler,

Fig. 3 is a fragmentary vertical section 55 more particularly illustrating the mounting of the reinforcing cleats for the oiler shoe, and

Fig. 4 is a fragmentary sectional view

particularly illustrating the manner in which the handle socket of the device is mounted upon the oil reservoir.

In carrying the invention into effect, I 60 employ a hollow oiler body 10. This body is preferably constructed of suitable sheet metal and is closed at its upper end by a top wall 11 while, at its lower end, the side walls of the body closely converge to define a re- 65 stricted discharge slot 12 extending the full length of the body. Fixed within the lower end portion of the body is a partition 13 providing the bottom wall of an oil reservoir 14. The top wall 11 is formed with 70 a filler opening for the reservoir and said opening is surrounded by a suitable up- 75 standing flange upon which is threaded a closure cap 15. Connected, as particularly shown in Fig. 4 of the drawings, to the rear side wall of the body, at a point substantially midway between the ends of the body, is a handle socket 16 braced by a reinforcing member 17 extending across the top wall of the body and removably fitted in said 80 socket is a handle 18 by which the device may be pushed about over a floor. Remov- 85 ably fitted upon the lower tapered end portion of the body 10 is a rubbing shoe 19. This shoe is preferably formed of two strips 90 of thick felt secured together at their ends in such manner that the shoe is, as particu- 95 larly shown in Fig. 1, adapted to fit snugly over the lower end portion of the body pro- jecting therebeneath. Interposed between the side walls of the body adjacent their lower edges are spacers 20 suitably secured to said walls and separated transversely of the body to prevent closing of the slot 12. Freely fitted through these spacers as well 100 as through said side walls and the strips of the rubbing shoe, are bolts or other suitable fastening devices 21 which are preferably equipped with wing nuts 22. The bolts 21 carry reinforcing cleats 23. These cleats 105 may be constructed of wood, metal or other approved material and are formed adjacent their ends with transverse slots 24 through which the bolts are freely received, the strips being arranged to overlie the sides of 110 the rubbing shoe. Thus, as will be clear, the strips 23 will provide rigid reinforcements for the shoe and by properly manipulating the wing nuts 22, may be adjusted vertically of the shoe.

In use, it is intended that the oiler will be manipulated by grasping the handle 18 and

moving the oiler about over a floor, the shoe contacting at its lower free margin with the floor for distributing oil thereto. Consequently, it will be seen that the cleats 23 will, in the practical use of the device, prevent buckling of the shoe or distortion thereof such as would interfere with the uniform contact of the shoe throughout its length with the floor. The reinforcing cleats will thus tend to materially prolong the efficiency of the device as well as assist in the even distribution of the oil to the floor. As the shoe wears away at its lower free margin, the reinforcing cleats may be adjustably retracted. Normally, the cleats are, as particularly shown in Fig. 3, arranged to project below the lower end of the body 10 and will thus hold the lower margins of the strips of the shoe firmly together to provide a compact rubbing surface. However, since the cleats do not extend to the bottom edge of the shoe, a portion of the lower margin of the shoe is left free to flex or give as the shoe is moved over a floor for thus evenly distributing the oil to the floor and, of course, the cleats may be adjustably positioned vertically of the shoe for either increasing or decreasing the unsupported portion of the lower margin of the shoe.

30 Suspended beneath the bottom wall 13 of the reservoir 14 is a horizontally arranged tubular distributor 25 closed at its ends and provided at its upper side with a series of longitudinally spaced discharge openings 26. Upstanding from the distributor at a point substantially midway of its ends is a lateral inlet pipe 27 snugly received through the wall 13 and connected to the upper end of said pipe is a head 28 upstanding within the reservoir, it being understood, of course, that a sealed joint is provided between the pipe 27 and the bottom wall of the reservoir. At its lower end the head is formed with a suitable flange 45 seating against said bottom wall and formed in the head are oppositely disposed passages 29. Secured to and depending from the top wall 11 of the body in vertical alinement with the head 28 is a sleeve 30 and threaded through this sleeve is a valve 31 provided with a reduced lower end portion slidably received through the head 28 and adapted to close the passages 29. The upper end portion of the valve projects freely through the reinforcing member 17 and is preferably equipped with a winged head 32 in order that the valve may be easily adjusted manually.

As will now be readily understood, the 60 reservoir 14 may be filled with oil when, by properly adjusting the valve 31, oil will be permitted to flow from the reservoir into the distributor 25. The distributor will thus be filled with oil and when so filled oil will 65 overflow from the distributor through the

openings 26 to drip through the slot 12 onto the lower margin of the rubbing shoe. Since the distributor is of a length to extend throughout the major portion of the length of the shoe, oil will thus be distributed 70 equally to the shoe practically throughout its entire length so that the lower margin of the shoe will be uniformly saturated throughout its extent for thus equally distributing the oil to a floor. I accordingly 75 provide an arrangement whereby likelihood of oiling a floor in light and heavy streaks will be effectually overcome. Flow of oil to the distributor and accordingly to the rubbing shoe, is, of course, controlled by 80 means of the valve 31 and in this connection it is to be noted that since the oil, in order to issue from the distributor, must overflow at the upper side thereof, distribution of oil from the distributor will stop 85 immediately at the time the valve is closed. Furthermore, this construction provides an arrangement whereby, when the device is not in actual use, oil contained within the distributor will not likely become spilled 90 therefrom.

Having thus described the invention, what is claimed as new is:

1. A device of the character described including a reservoir, a rubbing shoe associated therewith and having a lineal floor engaging edge, adjustable reinforcing elements on each side thereof movable along the rubbing shoe away from the edge thereof, a distributor in communication with the reservoir, and means for controlling the flow from the distributor. 95

2. A device of the character described including a reservoir, a rubbing shoe associated therewith, rubbing shoe reinforcing means adjustable to the wear of said shoe, a distributor extending longitudinally of the shoe and in communication with the reservoir, and means for controlling flow from the distributor. 105

3. A device for the purpose set forth comprising a reservoir having its side walls converging below its bottom, a rubbing shoe secured around said converging side walls and projecting below the same, a distributor supported between said converging walls below and in communication with the reservoir, said distributor being constructed to overflow and feed liquid to the shoe, and means for regulating the flow. 115

4. A device for the purpose set forth comprising a reservoir having its side walls converging below its bottom, a rubbing shoe secured around said converging side walls and projecting below the same, a distributor supported between said converging walls below and in communication with the reservoir, said distributor being constructed to overflow and feed liquid to the shoe, means for regulating the flow, and means for main- 120

125

130

taining the lower edges of the side walls in spaced relation.

5. A device of the character described including a reservoir, a rubbing shoe associated therewith and having a surface engaging edge, and reinforcing means adjustable away from said edge to compensate for wear of said shoe.

6. A device of the character described in-

cluding a reservoir, a rubbing shoe associated therewith and formed of overlapping plies, and means for holding said plies together adjacent the rubbing surface of the shoe, said means being adjustable for wear of the plies.

In testimony whereof I affix my signature.

PRESTON BELVIN. [L.S.]
